LIFT FOR SUCKER RODS, PIPES, AND THE LIKE

Filed Dec. 1, 1924

Inventor
WALTER W. DONNELLY

By *A. L. Jackson*
Attorney

UNITED STATES PATENT OFFICE.

WALTER W. DONNELLY, OF FORT WORTH, TEXAS.

LIFT FOR SUCKER RODS, PIPES, AND THE LIKE.

Application filed December 1, 1924. Serial No. 753,381.

My invention relates to fishing tools and more particularly to a sucker rod or pipe lift and to a combination of slips for engaging rods and pipes and a pipe or sucker rod lift; and the object is to provide a new fishing tool and particularly to provide a combination fishing tool which is adapted to engage and lift rods and pipes and to lift a sucker rod by means of the weld or square. Another distinguishing feature of this invention is that the lifting member is not supported by springs and rivets in operation. Other objects and advantages will be fully explained in the following description and the invention will be more particularly pointed out in the claims.

Reference is had to the accompanying drawings which form a part of this application.

Fig. 1 is a side elevation of the combination tool. Fig. 2 is an enlarged view, showing a vertical section of the lift and the shoulder for the lift. Fig. 3 is a plan view of the lift and the casing therefor, showing the shoulder or base for the lift. Fig. 4 is an inverted plan view of the lift. Fig. 5 is a horizontal section of the lift casing above the shoulder or base.

Similar characters of reference are used to indicate the same parts throughout the several views.

The upper member 1 of the tool is provided with slips 2 for pulling rods and pipes and the slips 2 are forced downwardly by a spring 3. The lower member 4 includes the casing 4 for the lift 5. The lift 5 comprises a body having two arms 6 which constitute the grab and an attaching shank 7. The lift 5 is pivotally connected to the casing 4 which has a vertical slot 8 therein to permit the operation of the lift. The lift 5 is pivotally connected to the casing 4 by a pivot bolt 9. A spring 10 is coiled about the bolt 9 and one end is inserted in a hole in the seat 11 and the other end bears against the upper side of the lift 5 for holding the lift 5 yieldingly downward. The object is to provide a positive means for holding the lift down and making certain the falling of the lift to engage the sucker rod. Means are provided for supporting the lift so that there will be no strain on the pivot bolt. The lift is supported on a base or shoulder 12 which is integral with the casing 4 and crescent shaped. The lift

5 has supporting members 13 which rest on the base 12 when pulling a sucker rod. The general passage 14 through the casing 4 is off-set relative to the casing 4 so that the weld or square or box or pin of a sucker rod or a collar of a pipe may pass freely therethrough and the passage is large enough in diameter and the off-set in the casing adjacent the shoulder 12 is sufficient to permit the passage of the larger members of the sucker rod, that is, the weld or box or pin, and of a pipe, that is, the collar on the pipe, to pass upwardly and force the lift 5 back over the shoulder 12; and as soon as the larger members of the sucker rod and of the pipe pass above the lift 5, the spring 10 will throw the lift 5 downwardly so that it will engage the sucker rod below the weld or box and, if a pipe, the lift will engage the pipe below the collar, so that the arms 6 will lift the sucker rod or pipe out of the well. The weld or box of the sucker rod and collar of a pipe cannot pass back downwardly below the lift when once they have passed above the lift. The sucker rod or pipe will be caught in the throat 15.

The lower end of the casing 4 has a longer beveled portion 16 on that side of the casing 4 below the shoulder 12 and a shorter beveled portion 17 for aiding in centering the articles to be pulled in the passage 14.

Various changes in the sizes, proportions, construction and arrangement of the several parts may be made without departing from my invention.

What I claim, is,—

1. A fishing tool having a casing provided with a passage for the heads of sucker rods and for the passage of pipes and a crescent-shaped shoulder off-set in one side of said passage, a lift pivotally mounted in one side of said casing above said shoulder and provided with arms for catching under the welds of sucker rods and under the collars of pipes for lifting purposes, and shoulders depending from said lift on both sides of the pivotal connection and flat on the bottom edges and resting on said crescent-shaped shoulder to support said lift on said shoulder.

2. A fishing tool having a casing provided with a passage off-set in one side of said casing for the heads of sucker rods and for the passage of pipes, a flat crescent-

shaped shoulder extending the greater portion about said passage, a lift pivotally mounted in one side of said casing above said shoulder and held yieldingly on said shoulder and provided with arms for catching under the welds of sucker rods and under the collars of pipes, and flat bottomed shoulders depending from said lift and

adapted to rest on said crescent-shaped shoulder to support said lift on said shoulder and for preventing strain on said pivotal connection.

In testimony whereof, I set my hand, this 24th day of November, 1924.

WALTER W. DONNELLY.
